(57) **CLAIM**

(***) Term: **14 Years**

The ornamental design for a front panel for an electronic appliance cabinet, as shown and described.

(21) Appl. No.: **29/134,609**

DESCRIPTION

(22) Filed: **Dec. 22, 2000**

FIG. 1 is a front perspective view of a front panel for an electronic appliance cabinet in accordance with our design; FIG. 2 is a front elevational view thereof; FIG. 3 is a top view thereof; FIG. 4 is a left side view thereof, the right side being a mirror image of the left side; and, FIG. 5 is a bottom view thereof.

(51) LOC (7) Cl. **14-02**

The broken lines provided in the above views are used to indicate environmental structure and form no part of the design.

(52) U.S. Cl. **D14/446**
